MAGNETIC LID-HOLDING ATTACHMENT FOR A CAN OPENER

William E. Gundelfinger, St. Louis County, Mo.

Application May 16, 1951, Serial No. 15,196

Term of patent 7 years

(Cl. D22—2)

To all whom it may concern:

Be it known that I, William E. Gundelfinger, a citizen of the United States, residing in the county of St. Louis, State of Missouri, have invented a new, original, and ornamental Design for a Magnetic Lid-Holding Attachment for a Can Opener, of which the following is a specification, reference being had to the accompanying drawing, forming a part thereof.

In the drawing:

Fig. 1 is a top plan view;
Fig. 2 is a side elevational view;
Fig. 3 is an end elevational view;
Fig. 4 is an opposite end elevational view; and
Fig. 5 is a bottom plan view, all showing my new design for a magnetic lid-holding attachment for a can opener.

I claim:

The ornamental design for a magnetic lid-holding attachment for a can opener, substantially as shown.

WILLIAM E. GUNDELFINGER.
